UNITED STATES PATENT OFFICE.

HANS PETER HANSEN, OF NEW YORK, N. Y.

TYPE-SETTING MACHINE.

1,188,763.

Specification of Letters Patent. Patented June 27, 1916.

Original application filed September 20, 1911, Serial No. 650,400. Divided and this application filed February 28, 1914, Serial No. 821,700. Renewed November 20, 1915. Serial No. 62,638.

To all whom it may concern:

Be it known that I, HANS PETER HANSEN, a citizen of Denmark, residing at 1496 Vyse avenue, New York city, county of Bronx, 5 and State of New York, have invented certain new and useful Improvements in Type-Setting Machines, of which the following is a specification.

This invention relates to a typesetting machine of novel construction and more particularly to novel means for assorting type and automatically conveying type of like sort to their proper storing places from which they may be successively removed by 15 the typesetting mechanism proper.

This application is a division of an application filed by me September 20, 1911 under Serial number 650,400.

In the accompanying drawing: Figure 1 20 is a side elevation, partly broken away, of type assorting means embodying my invention, Fig. 2 a top view thereof, Fig. 3 a vertical section on line 3—3, Fig. 2, Fig. 4 an enlarged sectional elevation of the right 25 hand end of Fig. 3, Fig. 5 an end view of Fig. 4, Figs. 6 and 7 are respectively a front view of the rear type-carrying bar, and a rear view of the front type-distributing bar, the bars being shown in a position which 30 they will assume by tilting them outward on their lower longitudinal edges, Fig. 8 is an end view of the assembled bars and intermediate type, Fig. 9 a perspective rear view of the front bar and of a type engaged thereby, 35 and Fig. 10 shows a number of types in side view.

The upper portion of the machine frame 10 supports a traverse 11 provided with bearings 12 for the main driving shaft 13. 40 The latter is by a suitable worm drive 14 connected to the vertical shaft 15 of a type cylinder or receptacle 16, shaft 15 being journaled in a step bearing 17 and in traverse 11. Cylinder 16 is provided with a plurality of peripherally arranged longitudinal pockets or magazines 18 that are adapted 45 to contain type 19 of mixed sort. The pockets 18 which are open at their ends and along the circumference of the cylinder, are 50 of such a depth as to expose the heads 20 of type 19 as clearly illustrated in Fig. 3. The bottom type of each pocket 18 rests upon a stationary plate 21 which is provided with 55 an opening 22 adapted for the passage of a type 19 and located above a chute 23 for such

type. As thus far described, it will be seen that shaft 13 imparts to cylinder 16 a relatively slow rotary movement. As the pockets 18 become thus consecutively alined with opening 22, the bottom type of such pockets 60 are successively discharged into chute 23 to be then assorted in manner hereinafter described. In order to permit but the bottom ever such pocket arrives above opening 22, a checking member 24 is provided. The latter 65 is furnished with a pair of upper spaced type of each pocket 18 to be released when ribs 25 which, during the rotation of cylinder 16 engage the reduced sections 26 of the second type from the bottom so that but the 70 bottom type of each stack is permitted to drop while traveling across opening 22.

The chute 23 is so formed as to tilt the type delivered through slot 22, from a horizontal position into a vertical position face downward, for which purpose, said chute is composed of an upper vertical portion and a lower quadrantal portion. Chute 23 is provided with a pair of opposed guide rails, 75 each rail being likewise composed of an upper vertical portion 27 and a lower quadrantal portion 27^a. These rails are adapted to be engaged by a pair of opposed recesses 28 formed between the head 20 and a pair of 80 guide ribs 29 extending laterally from the type-body and located in proximity to the head. The type are conveyed along said rails by means of the fingers 30 of an endless 85 feed chain 31. The latter engages corresponding sprocket wheels of a pair of shafts 32, 33, the shaft 32 being driven from a shaft 34 through worm drive 35, spindle 36 and beveled gear wheels 37. The fingers 30 depending from the lower run of chain 31, are 90 accommodated within a passage 38 formed between a pair of horizontally disposed type-distributing bars 39, 40, passage 38 constituting a continuation of chute 23. The fingers 30 are so spaced and are driven with 95 such a speed relatively to that of cylinder 16, that but a single type is received between each pair of adjacent fingers 30. As clearly 100 illustrated in Fig. 4, the type are properly guided by rails 27 during their travel through chute 23, the lower quadrantal rail portions 27^a being arranged concentrically to shaft 33. After leaving chute 23, the type 105 travel along bars 39, 40 and are here suspended face downward by means of peculiarly arranged rails extending inwardly 110

from said bars, to be finally dropped off said rails at different points. The latter are so selected as to cause the released type to drop into a channel that conveys the same to 5 the place at which type of like sort are stacked.

As is apparent from Figs. 6, 7 and 9, the front bar 39 is provided with a plurality of sets of type-releasing rails 41 which sets are numbered I to IX. The rails of each set 10 are arranged above one another and increase in length from bottom to top, whereas they are so disposed on bar 39 that their right hand ends are in substantially vertical alignment (Fig. 7) while their left hand ends 15 form a stepped line. The top rails of each set are separated from one another by intervening gaps 42 as clearly illustrated in Figs. 7 and 9. Bar 40 is provided with inwardly extending type-carrying rails 43 arranged likewise above one another, the number of said rails being one less than that of the sets of rails 41. The rails 43 also increase in length from bottom to top, the 20 right hand ends thereof being arranged in substantially vertical alignment and coinciding with the right hand end of set I of rails 41, while the left hand end of any rail 43 terminates at the right hand end of the 25 co-operating set of rails 41. In other words the first rail 43¹ terminates at the right hand end of the set II of rails 41, the second rail 43² terminates at the right hand end of set III and so on, the longest rail 43⁸ terminating at 30 the right hand end of set IX of rails 41.

In addition to the guide ribs 29, the type are provided with type-carrying ribs 44 and type-releasing ribs 45 said ribs extending from opposite sides of the type-body. Ribs 40 44, 45 are differently disposed for different sorts of type, each individual sort being distinguished over the other type by a characteristic arrangement of said ribs. Each rib 44 is designed for engagement with a selected rib 43 of a bar 40, while each rib 45 is designed for engagement with a selected rib 41 of bar 39. The several type are subdivided into classes the number of which corresponds to the number of sets of rails 41 and 45 vice versa. The type of each class have carrying ribs 44 of like disposition so as to be fed along one and the same rail 43 to that set of rails 41 from which they are to be consecutively released. Thus for instance, the 50 type 19^a, 19^b (Fig. 10) are provided with carrying ribs 44 that are designed to be supported by the top rail 43⁸. After leaving rail 43⁸, the type 19^a will be suspended by means of rib 45 from the top rail 41⁹ of set 55 IX until it loses its support and thus drops into a channel 46 which is adapted to convey the same to the storing place of type of like sort (not shown). The type 19^b will also be supported by its rib 44 on rail 43⁸, 60 while its rib 45 will then engage one of the

shorter rails 41 of set IX, say rail 41^b to be dropped into its individual channel 46. Type 19^c will be carried along rail 43⁷ to be released by one of the shorter rails 41 of set VIII, etc. On some of the type, the releasing rib 45 is missing, in which case the type is dropped as soon as it has left the carrying rail 43 that heretofore supported the same. Thus for instance the type 19^d will be released immediately after its rib 41 has left 75 say rail 43⁵. Finally with the type 19^e both of the ribs 44, 45 are missing, so that the type will be released immediately after leaving guide rail portion 27^a. Thus 19^e illustrates the type which is first released while 19^e 30 represents the type last discharged.

It is obvious that there must be a limited play between rails 27^a and between the heads 20 and ribs 29 of the type in order to prevent jamming of the type. As this play would 85 permit a slight tilting of the type on the horizontal terminal 27^b of the chute-rail which might tend to prevent a proper engagement of the type-ribs 44, 45 with the assorting rails 43, 41, a comparatively short 90 rail 47 is provided on bar 40 that is slightly spaced from rail 27^b and is designed to engage the upper face of one of the ribs 29. This rail 47 will right the type and thus 95 effect a proper engagement of the same with ribs 41, 43.

It will be seen that by my invention novel and effective means are provided for automatically assorting mixed type so that type of like sort may be gathered at their individual storing places ready for the subsequent setting operation.

I claim:

1. In a device of the character described, a substantially horizontal type-passage 105 adapted to accommodate a type, a plurality of type-carrying rails arranged above one another and formed at one side of said passage, said rails increasing in length from bottom to top, a plurality of sets of type-releasing rails likewise arranged above one another and formed at the other side of said passage, the type-releasing rails of each set also increasing in length from bottom to top, and means for feeding the type 110 along said passage.

2. In a device of the character described, a movable receptacle having vertically arranged open-ended type-pockets adapted to contain type of mixed sort, a type-chute, 120 means for discharging the bottom type from consecutive pockets into said chute, a substantially horizontal type-passage adapted to accommodate the type face downward, a first set of type-carrying rails gradually increasing in length from bottom to top and formed at one side of said passage, a plurality of second sets of type-releasing rails formed at the other side of the passage, the type-releasing rails of each second set like- 125

wise gradually increasing in length from bottom to top, both of the first and second rail-sets being adapted to be engaged by the type, means for conveying the type from 5 the chute toward the type-passage and along said passage, and type-receiving channels arranged below the type-passage.

3. In a device of the character described, a rotatable type-cylinder having vertically 10 arranged open-ended type-pockets adapted to contain stacks of mixed type, a stationary plate mounted below the cylinder for supporting the bottom type of said stacks, said plate being provided with a slot with 15 which the type-pockets are adapted to register, means located in proximity to said slot for retaining the second type from the bottom while a pocket registers with said slot, a curved type-chute communicating 20 with the slot, means for guiding the type discharged from the slot along said chute, a substantially horizontal type-assorting passage communicating with said chute, and means for feeding the type along said passage.
- 25 4. In a device of the character described, a pair of substantially horizontal spaced bars that form an intervening passage

adapted to receive a type face downward, a plurality of type-carrying rails arranged above one another and extending from one 30 of said bars into the passage, said rails increasing in length from bottom to top, a plurality of sets of type-releasing rails likewise arranged above one another and extending from the other bar into the passage, 35 the type-releasing rails of each set also increasing in length from bottom to top, and means for feeding a type along said passage.

5. In a device of the character described, a substantially horizontal passage adapted to 40 accommodate a type face downward, said passage being provided with type-carrying rails that increase in length from bottom to top and with sets of type-releasing rails, 45 the rails of each set likewise increasing in length from bottom to top, while the type is furnished with a pair of ribs, one rib being adapted to engage a selected type-carrying rail and the other rib being adapted to engage a selected type-releasing rail.
